UNITED STATES PATENT OFFICE

161,915

CANISTER

Martin Gaber, Chicago, Ill., assignor to Peter Pan Products Inc., Chicago, Ill., a corporation of Illinois

Application July 29, 1950, Serial No. 11,486

Term of patent 3½ years

(Cl. D58—15)

To all whom it may concern:

Be it known that I, Martin Gaber, a citizen of the United States, residing at 2724 West Granville, city of Chicago, county of Cook, and State of Illinois, have invented a new, original, and ornamental Design for a Canister, of which the following is a specification, reference being had to the accompanying drawing, forming a part hereof.

I claim:

The ornamental design for a canister, as shown.

MARTIN GABER.
